(57) **CLAIM**

The ornamental design for a device for wringing a mop, as shown and described.

DESCRIPTION

FIG. 1 is a right side view of the device for wringing a mop of the instant invention;

FIG. 2 is a left side view of the device for wringing a mop of the instant invention;

FIG. 3 is a perspective view showing the front and right side of the device for wringing a mop of the instant invention;

FIG. 4 is a perspective view showing the front and left side of the device for wringing a mop of the instant invention;

FIG. 5 is a front view of the device for wringing a mop of the instant invention;

FIG. 6 is a top view of the device for wringing a mop of the instant invention;

FIG. 7 is a bottom view of the device for wringing a mop of the instant invention;

FIG. 8 is a perspective view showing the rear and right side of the device for wringing a mop of the instant invention;

FIG. 9 is a rear view of the device for wringing a mop of the instant invention; and,

FIG. 10 is a perspective view illustrating the rear and left side of the device for wringing a mop of the present invention.
